Attorney

UNITED STATES PATENT OFFICE.

DAVID B. ASHMAN, OF BALTIMORE, MARYLAND, ASSIGNOR TO THE GOLDBERG PAD-DING MACHINE COMPANY, OF CINCINNATI, OHIO, A CORPORATION OF OHIO.

MACHINE FOR SLITTING PLIES OF FABRICS.

Application filed September 28, 1921. Serial No. 503,762.

To all whom it may concern:

Be it known that I, DAVID B. ASHMAN, a citizen of the United States of America, and a resident of Baltimore, in the county of Baltimore City and State of Maryland, have invented a new and useful Improvement in a Machine for Slitting Plies of Fabrics, of which the following is a specification.

10 This invention relates to a machine for cutting slits in plies of fabrics, and is especially useful in placing the slits in such places where pockets are to be formed in garments made from said fabrics.

15 An object of my invention is to provide a machine for the purpose stated that will be simple in construction and operation, and that will readily cut through plies of fabrics of considerable thickness.

20 Another object is to provide a device for the purpose stated which is adapted to slit the material intermediate the side edges thereof, and which, during such cutting, is adapted to secure the material against movement, whereby neat and trim apertures may be formed in the fabrics preparatory to the formation of the pockets at such places.

These and other objects are attained by the means described herein and disclosed in 30 the accompanying drawings, in which—

Fig. 1 is a side elevation of a device embodying my invention.

Fig. 2 is a rear elevation of the device shown in Fig. 1.

35 Fig. 3 is a sectional view on line 3—3 of Fig. 2.

Fig. 4 is a sectional view on line 4—4 of Fig. 2.

Fig. 5 is an enlarged sectional view on 40 line 5—5 of Fig. 2.

My invention comprises a base a over which a frame a^2 supports a knife a^3 , and means adapted to reciprocate the knife, whereby the knife may cut through the fabrics B placed upon the base.

45 The device A of my invention comprises a base a having an elongated slot a' therein, and upon which is mounted a frame a^2 having arms a^3 and a^4 which extend over the base a and terminate substantially midway between the forward and rear ends of the base. The free ends of the arms extend toward the forward end of the base and are spaced from one another by means 55 of a brace a^5 . The arms have mounted

upon them, at their forward ends, the slotted tubes a^6 and a^7 . A knife holder a^8 is slidably mounted upon the tubes and supports a downwardly projecting knife a^9 , which knife may be mounted upon said holder in any suitable manner. The knife has an angular cutting edge a^{10} . The knife holder has formed in it a vertical way a^{11} in which is reciprocally mounted a rod a^{12} , the upper end of which rod is mounted upon a cross bar a^{13} . The opposite ends of the cross bar carry pins a^{14} and a^{15} , which pins extend into the slots a^{16} and a^{17} in the tubes. The knife holder carries pins a^{18} and a^{19} which extend into the slots a^{15} and a^{16} . Springs a^{20} and a^{21} are disposed within the tubes and the opposite ends of the springs engage the pins on the knife support and on the cross bar. A plate a^{22} mounted on the knife support limits the forward end of the way a^{10} and serves to retain the rod in the way a^{10} . The rod a^{11} carries at its lower end, a slotted pressure foot a^{23} , the slot therein being in the line of reciprocation of the knife a^9 and of a size that will permit the projection of the knife therethrough. Studs a^{24} and a^{25} extend from the knife support and pivotally mount the levers a^{26} and a^{27} upon the knife support. The upper ends of the levers are retained in spaced relation by means of a handle a^{28} , and suitable means such as the screws a^{29} retain the handle upon such levers. The lower ends of the levers are pivotally connected to the upper ends of the links a^{30} and a^{31} , the lower ends of said links being pivotally mounted upon the forward ends of the arms a^3 and a^4 . The rod a^{11} has formed upon it a shoulder a^{32} which normally engages the upper surface of the knife support. The rod also has formed on it a lug a^{33} in which is formed a vertical guide way in which the knife may be reciprocated and the upper end of the lug a^{33} forms a shoulder a^{34} adapted to engage the under surface of the knife support.

The operation of my device is as follows:

Plies of fabric B are inserted between the base a and the arms a^3 and a^4 in such position that the knife, when being brought downward, will cut the fabrics in the desired place. The handle a^{28} is then grasped and the levers are moved about their pivotal mounting upon the studs a^{24} and a^{25} , whereupon the knife support and cross bar are

moved downwardly and carry the knife and pressure foot towards the fabrics B. After the pressure foot α^{21} is brought into engagement with the fabrics B, the springs α^{19} and α^{20} retain the pressure foot in yielding engagement upon the fabrics. As the levers α^{24} and α^{25} are moved further about their pivotal mountings, the knife engages the fabrics and cuts a slit therein. The knife 10 may be moved downwardly until the lower surface of the knife support engages the shoulder α^{32} formed on the lugs α^{31} , whereupon the lever is returned to its normal position as shown in Fig. 2, whereupon the 15 knife is withdrawn from the materials B and the pressure foot is elevated thereabove, thereby releasing the fabrics.

What I claim is:

1. In a device for slitting plies of fabrics 20 the combination with a flat base having two spaced apart tubes extending vertically thereabove, of a knife support having a tubular bearing at each end which bearings slide on the exterior of the tubes so as to 25 sustain the support in horizontal position between the tubes, means to reciprocate the knife support upon the tubes, and a depending knife mounted on the support.
2. In a device for slitting plies of fabrics 30 the combination with a flat base having two spaced apart tubes extending vertically thereabove, of a knife support having a tubular bearing at each end which bearings slide on the exterior of the tubes so as to 35 sustain the support in horizontal position between the tubes, means to reciprocate the knife support upon the tubes, a depending knife mounted on the support, and a pressure foot adapted to be moved into yielding 40 engagement with the base.
3. In a device for slitting plies of fabrics 45 the combination with a flat base having two spaced apart tubes extending vertically thereabove and each tube having a longitudinal slot therein, of a knife support having a tubular bearing at each end which bearings slide on the exterior of the tubes so as to 50 sustain the support in horizontal position between the tubes, means to reciprocate the knife support upon the tubes, a depending knife mounted on the support, springs in the tubes, a rod mounted reciprocally upon the support, a cross bar upon the 55 upper end of the rod, pins upon the cross bar and upon the support extending into the slots in the tubes and engaging the springs, and a pressure foot mounted upon the lower end of the rod.
4. In a device of the class described the 60 combination with a base of spaced apart tubes extending above the base, a knife support having tubular bearings which slide on said tubes, a knife movable with the support and normally having its cutting edge above 65 the base, levers pivotally mounted intermediate their ends upon the support, links connecting an end of each lever and having a pivotal mounting upon the tubes adjacent the lower ends thereof, the links and levers being adapted to move the knife support 70 upon the tubes.

5. In a device of the class described the combination with a base of spaced apart tubes extending above the base, a knife support having tubular bearings which slide on said tubes, a knife movable with the support and normally having its cutting edge above the base, levers pivotally mounted intermediate their ends upon the support, links connecting an end of each lever and having a pivotal mounting upon the tubes adjacent the lower ends thereof, the links and levers being adapted to move the knife support 75 upon the tubes.

6. In a device of the class described the combination with a base of spaced apart tubes 80 extending above the base, a knife support having tubular bearings which slide on said tubes, a knife movable with the support and normally having its cutting edge above the base, levers pivotally mounted intermediate their ends upon the support, links connecting an end of each lever and having a pivotal mounting upon the tubes adjacent the lower ends thereof, the links and levers being adapted to move the knife support 85 upon the tubes, and a pressure foot adapted to be moved toward and away from the base simultaneously with the movement of the knife toward and away from the base.

7. In a device of the class described the combination with a base of spaced apart tubes 90 extending above the base, a knife support having tubular bearings which slide on said tubes, a knife movable with the support and normally having its cutting edge above the base, links connecting an end of each lever and having a pivotal mounting upon the tubes adjacent the lower ends thereof, the links and levers being adapted to move the knife support 95 upon the tubes, a pressure foot adapted to be moved toward and away from the base simultaneously with the movement of the knife toward and away from the base, and means to yieldingly retain the pressure foot in engagement upon the tubes.

8. In a device of the class described the combination of a slotted base, arms mounted 100 on the base and extending thereabove, tubes mounted on the arms extending upwardly therefrom, a knife support mounted slidably upon the tubes, a knife mounted upon the support and having a depending cutting edge adapted to enter into the slot in the base, a lever pivotally mounted intermediate 105 its ends upon the knife support, and a link having its opposite ends pivotally mounted upon one of the arms and upon one of the 110 ends of the lever.

9. In a device of the class described the combination of a slotted base, arms mounted 115 upon the base and extending thereabove, slotted tubes mounted upon the arms and extending upwardly therefrom, a knife support mounted slidably upon the tubes and having a way extending therethrough, a knife mounted upon the support and having a depending cutting edge adapted to be inserted into the slot in the base, a cross bar, 120 a rod mounted on the cross bar and extending reciprocally through the way in the support, pins on the opposite ends of the cross bar extending into the slots in the 125 support, pins on the opposite ends of the cross bar extending into the slots in the 130 support.

- tubes, pins on the support extending into the slots in the tubes, a spring in each tube engaging the pins on the cross bar and the support, a slotted pressure foot mounted upon the lower end of the rod and normally lying between the base and the cutting edge of the knife, the slot in the pressure foot being in alignment with the knife and the slot in the base, a lever pivotally mounted intermediate its ends upon the knife support, and a link pivotally mounted upon an arm pivotally engaging the lower end of the lever.
- 5 In testimony whereof, I have hereunto subscribed my name this 12th day of 15 September, 1921.

DAVID B. ASHMAN.
